COMBINED CANDLEHOLDER AND CHRISTMAS TREE ORNAMENT

Dario Moranduzzo, Via Aretina 161, Florence, Italy

Filed Sept. 22, 1966, Ser. No. 3,962

Term of patent 14 years

(Cl. D48—2)

FIG. 1 is a side elevational view embodying my new design, the opposite side being substantially identical; and FIG. 2 is a right-hand perspective view embodying my new design, the left-hand perspective view being substantially identical.

I claim:

The ornamental design for a combined candleholder and Christmas tree ornament, as shown and described.
